UNITED STATES PATENT OFFICE

2,625,905

APPARATUS FOR APPLYING COATING MATERIAL TO PIPE

Sidney Lee Richards, Jr., Corpus Christi, Tex., assignor to Rosson-Richards Processing Co., Inc., Corpus Christi, Tex., a corporation

Application April 13, 1950, Serial No. 155,724

3 Claims. (Cl. 118—320)

1

This invention relates to apparatus for applying coating material to pipe, and more particularly to a machine for treating pipe whereby the same may be coated with concrete or the like.

The invention has special application in the preparation of pipe for use in the construction of pipe lines in which certain portions of the line must be weighted, as by coating the same with concrete, to prevent floating in water or in locations where the soil is in a condition to produce a buoyant effect on such pipe.

It is the principal object of the invention to provide coating apparatus embodying mechanism for supporting pipe in position to be coated, and rotating and moving the pipe while applying the coating material to the same, whereby a layer of material of substantially uniform thickness may be applied throughout the entire area coated.

A further object of the invention is the provision of means for continuously feeding coating material to the zone of application of the same, in accordance with the rate of rotation and longitudinal movement of the pipe, to assure uniformity of the coating thereon.

Another object of the invention is to provide, in coating apparatus of the type referred to, means for accurately adjusting the relationship between the feeding mechanism and the pipe being coated, in order to minimize waste of coating material and assure uniformity of the coating obtained.

Another object of the invention is to provide coating apparatus embodying means for mixing the coating material and continuously feeding the same to the zone of application, and means for returning waste material for remixing with additional coating material to be fed to the zone of application.

Another object is the provision in coating apparatus of means for controlling the mixing, feeding, and returning mechanism, as well as the rotation and movement of the pipe, so that the functioning of the apparatus may be coordinated to secure the most efficient and economical production of coated pipe.

A still further object is to provide pipe coating apparatus of simple design and rugged construction capable of withstanding the hard conditions of use and exposure to which such apparatus is likely to be subjected.

Other objects and advantages of the invention will be apparent from the following detailed description, constituting a specification of the same when taken in conjunction with the annexed drawings, wherein—

2

Figure 1 is a top plan view of the invention; Figure 2 is a cross-sectional view of the invention taken along the line 2—2 of Figure 1, looking in the direction indicated by the arrows;

5 Figure 3 is a perspective view partly broken away, showing the concrete delivering and applying means, together with the power plant and driving means for the same, with parts of the remaining structure of the machine including unessential details of the same removed;

10 Figure 4 is a perspective view partly broken away, showing the return mechanism for waste material, together with the power plant and driving means for such mechanism, with parts of the remaining structure of the machine and unessential details of the same removed; and

15 Figure 5 is a detail side elevational view, on a somewhat enlarged scale, showing the structural details of the brush adjusting means of the invention.

20 The invention, briefly described, comprises mechanism for supporting pipe horizontally for rotation about its longitudinal axis, and for moving the pipe while so rotating, in spaced relation to concrete applying apparatus including concrete feeding and spraying means and return means for waste material.

25 Referring to the drawings in greater detail the invention includes pipe supporting and rotating mechanism, best seen in Figure 1, wherein the numeral 10 indicates a driving carriage and 12 indicates a driven carriage, said carriages being operatively connected to move along a trackway having rails 14, and to rotatably support a pipe, such as is indicated at 16 to be moved past the concrete applying apparatus and rotated in spaced relation thereto.

30 The driving carriage 10 is preferably of generally rectangular construction and carries spaced pairs of wheels 18 and 20 mounted on shafts 22 and 24, respectively, which shafts are journaled in suitable bearings attached to spaced frame members of the carriage. The wheel pair 18 is operatively connected, by suitable means such as sprockets and driving chains, to a motor 26 whereby said wheels are rotated, and the wheel pair 18 is drivingly connected with wheel pair 20 so that both pairs of wheels are simultaneously rotated to rotate the pipe 16.

35 The driven carriage 12 has similar pairs of wheels 28 and 30 similarly mounted and adapted to turn freely upon rotation of the pipe 16. All of the wheels of the pairs are preferably provided with rubber tires for engagement with the pipe to assure rotation of the pipe. Both of the carriages are preferably provided with grooved wheels, as

indicated at 32, whereby the carriages may be moved along the rails 14.

A connector beam 34 is fixedly secured to the carriage 10 and is adjustably attached to the carriage 12, by suitable clamping means 36, so that the distance between the carriages may be adjusted to accommodate different lengths of pipe and the carriages are securely connected to be moved as a unit along the track.

From an inspection of Figure 1 of the drawing, it will be apparent that the pipe supporting and rotating mechanism described above makes it possible to support pipes of different length and diameters on the carriages, and rotate such pipes while moving the same along the track past the concrete applying apparatus in spaced relation thereto.

The concrete feeding and applying apparatus includes a mixing and feeding drum, indicated at 40, mounted on a supporting frame 42 for rotation on flanged rollers 44 journalled on the frame. The drum is rotated by means of suitable driving means such as a ring gear 46 and chain 48 through driving mechanism later to be described in greater detail.

Within the drum inwardly extending vanes 50 are provided, such that material in the drum is mixed by rotation of the same, and portions of such material are lifted by the vanes to the top of the drum from whence the material falls into a feeding hopper 52 inside the drum. The ends of the drum may be partly open and the hopper 52 is supported inside the drum by the tube 54 of a screw conveyor which projects through one end of the drum. A circular plate 53 may be supported in the end of the drum 40 by attachment to the tube 54 or otherwise, as shown in Figure 3. Mixed concrete from a concrete mixer, not shown, enters the drum 40 by way of the chute 58 of the concrete mixer and the chute 60 extending into the drum, as seen in Figure 2.

A feeding screw 62 is rotatably supported in the tube 54 and feeds the concrete from the hopper 52 into a second conveyor in the tube 64 having a feeding screw 66 rotatable therein, whereby the concrete is fed to a pair of high speed revolving brushes 68 and 70 mounted on horizontal shafts 72 and 74, respectively, by which brushes the concrete is propelled against the surface of the pipe 16. The brushes 68 and 70 may be made adjustable toward and away from each other by suitable means, such as shown in Figure 5, so that the distance between the brushes may be varied as desired and so that the brushes may be adjusted with relation to the axis of the pipe being coated.

Beneath the pipe 16 there is adjustably positioned a hopper 78, adapted to receive waste concrete falling from the pipe, and having one end of a feeding screw 80 therein whereby waste material is conveyed through the tube 82 extending into the end of the drum, back to the interior of the drum 40. The tube 82 has a rack 84 attached thereto with which a pinion 86 cooperates to move said tube inwardly or outwardly with relation to the drum, in order to adjust the position of hopper 78 beneath pipe 16 to catch the waste concrete, as will best be seen in Figures 2 and 4. A shaft 85 supported in suitable bearings carries the pinion 86, which shaft is adapted to be rotated by a hand wheel 87 for moving the waste return apparatus to adjust the hopper 78 in position beneath the pipe.

As shown in Figures 2 and 3 the brushes 68

and 70 are partially enclosed by a casing attached to the conveyor tube 64 and having hinged sides as indicated at 90 and a hinged top 92. The sides 90 are formed with arcuate cut out portions, so that pipe 16 may pass therethrough in spaced relation to the brushes 68 and 70, and the sides and top will serve to partially confine the concrete as the same is propelled against the pipe, to prevent spattering and waste of the coating material.

The brushes may be made adjustable by an arrangement such as that shown in Figure 5, wherein spaced apart vertical guides 69 and 71 are fixed to the sides of the casing in spaced relation thereto, and bearings 73 and 75 for the shafts 72 and 74 are slidably disposed between the guides. The bearings are adjusted by screws 77 and 79 carried in brackets 81 and 83 welded or otherwise secured between the guides at their upper and lower ends, the screws being provided with lock nuts 85 and 87.

The entire concrete applying apparatus may conveniently be supported on a frame indicated at 94 in Figure 2 whereby the apparatus can be positioned adjacent the rails 14 and spaced therefrom as may be desired.

The concrete feeding mechanism and a power plant and driving connections for the apparatus may be carried on a platform 96 resting on the supporting frame 94. The power plant is indicated at 98, positioned near one end of the platform 96, which power plant may take the form of an internal combustion engine or other suitable prime mover, having a rotatable driving shaft 100 operatively connected therewith. At its outer end the shaft 100 is supported in a suitable bearing 102, and at spaced intervals on the shaft pulleys 104, 106 and 108 are carried thereon. Pulley 104 is connected through the inter-mediation of a driving belt 110 to pulleys 112 and 114 fixed on shafts 72 and 74, respectively, to drive the high speed brushes 68 and 70. Belt 110 also passes about idler pulleys 116 and 118 to maintain the same in engagement with pulleys 112 and 114 and under proper tension.

Pulley 106 is connected by drive belt 120 with a pulley 122 on shaft 124 of a speed reducer mechanism 126 which is operatively coupled by a clutch 128 with a shaft 130 carrying sprockets 132 and 134 thereon. Shaft 124 is supported at its outer end in a bearing 136.

Sprocket 132 operates through a drive chain 138 passing over sprockets 140 and 142, to rotate a telescoping shaft 144, which in turn operates through universal joints 146 and 148 to turn a gear 150 located in a gear box 152 attached to the hopper 78. Gear 150 meshes with a gear 154 which meshes with a gear 156 attached to the feed screw 80 to rotate this screw for returning waste concrete from the hopper 78 through tube 82 to the drum 40.

Sprocket 136 is connected by means of drive chain 158 to a sprocket 160 mounted on a shaft 162 journalled in bearings 164 and 166 mounted on the frame 42. Shaft 162 carries a sprocket 168 thereon over which passes drive chain 48 which also passes about the ring gear 46, whereby the drum 40 is rotated.

Thus it will be seen that by operating the clutch 128 the rotation of the drum 40 and the operation of the waste concrete return conveyor can be controlled. A link mechanism including a rotatable shaft 172 and operating lever 174 therefor is connected to the clutch 128 for manual control of the same.

The rotation of the pulley 108 with shaft 100 is controlled by a clutch 178 whose engagement and disengagement is accomplished by a lever 180 suitably connected thereto. Pulley 108 operates drive belt 182 which passes about pulley 184 attached to the shaft 186 of a variable speed unit 188 of conventional construction. The variable speed unit is operatively connected to a right angle drive speed reducer 190 also of conventional design which drives a sprocket 192 connected by a drive chain 194 with sprocket 196 on a shaft 197, carried in space bearings 198 and 200, mounted on brackets suitably secured to adjacent supporting structure. Shaft 196 carries sprockets 202 and 204 thereon.

Sprocket 202 is connected by a drive chain 206 to sprocket 208 fixed on the shaft of the feed screw 62 in the tube 54, and sprocket 204 is connected by drive chain 210 to sprocket 212 fixed on the shaft of feed screw 66 in tube 64.

As will be evident from an examination of Figure 3, the lever 180 may be manually operated to engage or disengage the clutch 178 thus controlling the rotation of the pulley 108 and the operation of the feed screws 62 and 66 at will.

A clutch 214 on the shaft 100, located at the prime mover 98 is controlled by a lever 216 through a rod 218 connected to a lever 220, whereby the rotation of shaft 100 can be controlled when it is desired to stop or start the entire concrete applying apparatus.

Means is provided for moving the pipe supporting carriages 10 and 12 along the track, which means is particularly illustrated in Figures 1 and 4. A reel 222 is shown attached to the carriage 10, upon which reel an operating chain 224 is wound. The chain may be unreeled to any desired extent and the reel locked against rotation by a conventional ratchet and pawl mechanism 226 or any suitable means, and the end of the chain secured to the carriage 12 in any suitable manner as indicated at 228. The chain passes through actuating mechanism mounted on the platform 96, as seen in Figure 4 which mechanism includes an upper sprocket 230 and lower sprockets 232 and 234 rotating in suitable bearings mounted on the platform. The chain is engaged by the sprockets so that upon rotation of the same the chain is pulled in one direction or the other to propel the carriages along the track. The sprockets 230, 232 and 234 may be driven through the intermediation of a reversible gear mechanism operated by a sprocket 236, which is rotated by a drive chain 238 passing over a sprocket 240 mounted on a shaft 242 carried in bearings 244 and 246. Shaft 242 carries a pulley 248 connected by a drive belt 250 to a pulley 251 fixed on a shaft 252 driven by the speed reducer mechanism 126. Conventional clutch means may be operatively interposed between the sprocket 236 and the sprockets 230, 232 and 234, which clutch means is operable by a lever 254 connected to a bell crank 256 by a rod 258, the bell crank being in turn connected to the clutch means by rod 260. Thus upon engaging the clutch by movement of the lever 254 the sprockets 230, 232, and 234 are caused to turn by rotation of the shaft 100 and actuate the chain whereby the carriages are moved along the track feeding the rotating pipe past the concrete applying apparatus.

In making use of the invention as described above, the carriages 10 and 12 are adjusted to the right distance apart to accommodate the length

5 of the pipe to be coated, by releasing the clamping device 36 moving the carriages to the proper distance and retightening the clamp. The pipe is then placed horizontally on the pairs of supporting wheels on the carriages, and rotated thereon by operation of the motor 26 at suitable speed.

10 The shaft 100 is set in rotation through operation of the prime mover 98, and the clutch 128 engaged by movement of the lever 174, thereby starting the drum 40 to rotate and setting in motion the return feed screw 80 for returning waste material from the hopper 78 to the drum 40.

15 The concrete feeding mechanism is then set in operation by engaging the clutch 178 by movement of lever 180, which starts rotation of the feed screws 62 and 66, and since the brushes 68 and 70 are already rotating from the shaft 100, the concrete is propelled onto the pipe. By movement of lever 254, to engage the clutch means through which the sprockets 230, 232 and 234 are driven, the carriages are propelled along in the track carrying the rotating pipe along in front of the brushes, thus completely coating the surface of the pipe to any desired degree.

20 In the event that a pipe of different diameter is to be coated, it is merely necessary to change the position of the return hopper 78 by turning hand wheel 87, which operates shaft 85 carrying pinion 86, which by cooperation with rack 84 moves the tube 82 inwardly or outwardly until the desired position is reached.

25 A brush 262 may be attached to the hinged top 92 of the brush enclosing casing, which brush engages the coating on the pipe to aid in distributing the material evenly over the surface of the pipe, as best seen in Figures 2 and 3.

30 It will be apparent from the above description that the invention provides a pipe coating machine by which pipes of any desired length and diameter can be conveniently coated with concrete or the like to any desired thickness, and which is easily adjusted and controlled to operate with a maximum of facility and a minimum of expenditure of time and labor.

35 The invention has been disclosed in connection with a particular embodiment of the same, but it will be understood that this is for the purpose of illustration only, and numerous changes can be made in the construction and arrangement of the various parts, without departing from the spirit of the invention or the scope of the appended claims.

40 Having thus clearly shown and described the invention, what is claimed as new and desired to secure by Letters Patent is—

1. An apparatus for coating pipes and the like comprising supporting means rotatively carrying the pipe to be coated, said supporting means being movable in the direction of the axis of the pipe, a rotatable mixing drum for coating material, means for rotating the drum, a conveyor tube in communication with the drum, a pair 45 of cylindrical brushes rotatably mounted to receive between them coating material from the discharge end of the conveyor tube and propel said material against the pipe, means for rotating the brushes, a feed screw rotatably mounted 50 in the conveyor tube, means for rotating the feed screw to feed coating material to the brushes, a movably supported return tube opening into the drum, a hopper carried by said return tube and located beneath said pipe for receiving excess coating material from the pipe, said return

tube being in communication with the hopper, means for moving the return tube to adjust the position of the hopper beneath the pipe, a return screw rotatably mounted in the return tube, means for rotating the return screw to convey excess coating material from the hopper to the drum, and driving means for effecting rotation of the pipe and longitudinal movement of said supporting means relative to said brushes.

2. An apparatus for coating pipes and the like comprising supporting means rotatively carrying the pipe to be coated, said supporting means being movable in the direction of the axis of the pipe, a mixing drum for coating material, means for rotating the drum, a conveyor tube extending into the drum, a hopper in the drum mounted on the conveyor tube and in communication therewith, means in the drum operable upon rotation of the drum to feed coating material into the hopper, a pair of cylindrical brushes rotatably mounted to receive between them coating material from the discharge end of said conveyor tube and propel said material against the pipe, a feed screw rotatably mounted in the conveyor tube, means for rotating the feed screw to feed coating material from the hopper to the brushes, a movably supported return tube extending at one end into the drum, a receiver on the other end of the return tube located beneath the pipe and adapted to receive excess coating material from the pipe, means for moving the return tube to adjust the position of the receiver beneath the pipe, a return screw rotatably mounted in the return tube, means for rotating the return screw to convey excess coating material from the receiver to the drum, and driving means for effecting rotation of the pipe and longitudinal movement of the supporting means relative to the brushes.

3. An apparatus for coating pipes and the like comprising supporting means being movable in the direction of the axis of the pipe, means for actuating said supporting means to rotate the pipe and move the pipe longitudinally of its axis, a rotatably mounted mixing drum for coat-

5

ing material, means for actuating said drum, a conveyor tube extending into the drum, a hopper in the drum mounted on the conveyor tube in position to receive mixed coating material, means in the drum operable upon rotation of the drum to feed coating material into the hopper, a pair of cylindrical brushes rotatably mounted to receive between them coating material from the discharge end of said conveyor tube and to propel said material against the pipe, a feed screw rotatably mounted in the conveyor tube, means for actuating the feed screw to feed coating material from the hopper to the brushes, a movably supported return tube extending at one end into the drum, a receiver on the other end of the return tube located beneath the pipe and adapted to receive excess coating material from the pipe, means for moving the return tube to adjust the position of the receiver beneath the pipe, a return screw rotatably mounted in the return tube, means for actuating the return screw to convey excess coating material from the receiver to the drum, a source of power, and means operatively connecting said actuating means with said source and operable to effect simultaneous operation of said actuating means.
